UNITED STATES PATENT OFFICE.

ALONZO HOWARD, OF CHICAGO, ILLINOIS, ASSIGNOR, BY DIRECT AND MESNE ASSIGNMENTS, TO LIGHTNING SPARKER MANUFACTURING COMPANY, OF CHICAGO, ILLINOIS, A CORPORATION OF ILLINOIS.

IGNITION-CONTROLLING APPARATUS.

Application filed July 7, 1922. Serial No. 573,401.

To all whom it may concern:

Be it known that I, ALONZO HOWARD, a citizen of the United States, and a resident of Chicago, in the county of Cook and State 5 of Illinois, have invented certain new and useful Improvements in Ignition-Controlling Apparatus, of which the following is a specification.

My invention relates to ignition controlling apparatus for explosive engines, particularly those in automotive vehicles.

With present ignition systems full and complete explosion of all the gas of a charge is not always assured. Sometimes the single 15 spark applied is not sufficient to produce full explosion. Sometimes too the gases are not yet in proper condition for explosion when the spark is given. The result is loss of power and fouling of the engine. In 20 some instances attempt has been made to overcome these disadvantages by applying several spark plugs to a cylinder, but these plugs all spark at the same instant, and where the gas is not yet properly com- 25 pressed or mixed inefficient explosion there- of would take place. One of the main ob- jects of my invention is to provide for the production of a succession of sparks for each charge of gas in a cylinder so that 30 if one spark will not cause full and complete explosion, a second or follow-up spark will complete the work of ignition. In engines where there is high compression the resistance of current flow between the 35 points of the spark plug is correspondingly increased and a great part of the current energy is consumed in overcoming the resistance so that the remaining energy may not be sufficient to produce enough heat to 40 properly ignite the gas. Passage of high pressure current between the points of a spark plug will tend to ionize the gap but this requires expenditure of energy and often- times the energy remaining after ionization 45 cannot produce a spark hot enough for proper ignition. In accordance with my invention I apply a spark preferably at the point of normal ignition but follow up this spark by a second spark. The first spark 50 will thoroughly ionize the gap and reduce the resistance so that practically all the energy of the second spark will be devoted to exploding the gases, the follow-up spark being timed to take advantage of the ion-

ized condition established by the first spark. 55 In some ignition systems, particularly where the ignition current is of low frequency the time of sparking would be coincident with a zero point of the sine wave and there would be no sparking. By having a succession of sparks, such a condition cannot exist as one of the sparks must take place at a time when the current flow has some value.

Another important object of my invention 65 is to adapt the apparatus of the invention for easy application to Ford cars. My system utilizes the low tension generator of the Ford ignition system but dispenses with the complicated electrical vibrator mechanism 70 necessary in the Ford system and permits direct connection of the generator with the spark plugs through simple induction coil mechanism and under control of simple distributor mechanism, and with two distinct 75 and successive sparkings for each cylinder charge of gas.

On the accompanying drawing I show my improved apparatus and its operation, the particular apparatus shown being designed 80 for use on Ford cars. On the drawing,

Fig. 1 is side elevational view,
Fig. 2 is a plan view,

Fig. 3 is a front elevational view of the primary circuit controlling mechanism, 85

Fig. 4 is an elevational view of the inner side of the distributor mechanism,

Fig. 5 is a side elevational view of the distributor brush arm,

Fig. 6 is an elevational view of the inner 90 side of said arm,

Fig. 7 is an elevational view of the outer side of said arm and the cam of the primary circuit controlling mechanism,

Fig. 8 is a sectional view on plane 8-8, 95 Fig. 2,

Fig. 9 is a circuit diagram showing the connection and operation of the parts, and

Fig. 10 is a circuit diagram showing a modified arrangement.

The apparatus and arrangement shown is particularly adaptable for Ford equipment but it could be readily adapted for use with other types of vehicles. On the drawing E represents the frame of a Ford engine and C represents the cam shaft of the engine, the end of the shaft extending a distance in front of the frame to ordinarily receive the 105

timer which forms part of the regular Ford engine equipment. The mechanism shown on the drawing is designed to be applied to the shaft end in place of the regular Ford timer. It consists of the circuit controlling mechanism A, and the distributor mechanism B. The cylindrical housing or frame 1 of the circuit controlling mechanism is of a diameter to fit at its rear end in the cylindrical pocket 2 which is provided on the frame of the Ford engine concentric with the cam shaft. The annular base 3 of a housing 4 of the distributor mechanism fits into the opening 5 in the front wall of the housing 1 as clearly shown in Fig. 8. A spring finger 6 engages against the outer end of the housing 4 to hold it and the housing 1 together and to hold the housing 1 in the pocket 2, such spring finger being provided on the Ford engines and ordinarily used for holding the timer in place. Within the housing 1 a cam 7 is secured on the shaft end, the cam abutting through a hub or spacer ring 8 against the shoulder 9 of the shaft. The cam may be of metal but is preferably of fiber, bakelite or other suitable insulating material and as shown has the four cam teeth 10, 11, 12 and 13 extending from its cylindrical surface ninety degrees apart. In the path of these cam teeth upper and lower contact springs 14 and 15 are arranged within the housing 1. Extending through the cylindrical wall of the housing at one side thereof is the terminal post 16 which is insulated from the housing by the bushing or insulating material 17. On the opposite side of the housing are the terminal posts 18 and 19 insulated from the housing by bushings 20 and 21. The upper spring 14 is anchored at its one end to the housing by the head of the terminal post 18, the spring being bent to extend around the cam 7 and terminating at its free end in a contact point or block 22 for engaging with the contact block 23 extending from the terminal post 16. In order to adjust the contact 23 it is mounted on the head of the screw 24 which threads into the head of the post 16. The lower spring 15 is anchored by the head of the post 16 and deflects around below the cam 7 and terminates at its free end in a contact block 25 for cooperating with the contact block 26 which is adjustable by being mounted on the head of the screw 27 which threads into the head of the terminal post 19. Intermediate their ends the springs have the deflections 28 and 29 respectively forming abutments with which the teeth of the cam engage in order to move the springs from their respective contacts. Referring to Fig. 3 (dotted lines) and Fig. 9 the cam rotates in the direction indicated by the arrow and the arrangement of the spring deflections is such that when one of the teeth is in engage-

ment with the upper spring to disengage the contacts 22 and 23 the diametrically opposite tooth will be in advance of the abutment in spring 15 and will not engage with such abutment until after the other tooth 70 has released the spring 14. Engagement of a tooth with the abutment 29 causes disengagement of the contacts 25 and 26, and as the cam rotates the respective teeth will engage with the spring to cause contacts 22 75 and 23 to be first separated and then after a short time interval separation of the contacts 25 and 26.

For a four cylinder engine such as a Ford engine the cam will have four teeth and the two sets of contacts will be opened in succession four times for each revolution of the cam shaft. An arm 30 extending upwardly from the housing 1 is connected by a suitable rod (not shown) with the spark lever 85 at the steering wheel of the machine the operation of which lever will cause rocking of the housing and adjustment of the spring abutments relative to the cam in order to advance or retard the sparking as desired. 90

The cam has the hub 31 extending forwardly on the shaft end and in the key way 32 is inserted the key 33 for locking the cam to the shaft against rotation thereon, this key forming a part of the Ford engine equipment for securing the timer contact arm to the shaft. The hub 31 is hexagonal on the exterior and the hexagonal nut 34 which also forms part of the regular Ford equipment is applied to the threaded end 100 of the shaft to abut against the hub and hold the inner end of the cam structure against the shaft shoulder 9. To prevent lubricating oil working its way into the housing 1 a felt bushing 35 is supported by the wall 105 36 at the inner end of the housing 1, the bushing intimately surrounding the shaft or the spacing member 8. This prevents leakage of oil into the housing 1 and the contact controlled by the cam will remain 110 clean to operate efficiently in the control of circuits to be referred to later.

The housing 4 has the cylindrical chamber 37 concentric with the shaft C and in this chamber travels the distributor member 38 which has the extension 39 for supporting the brush 40. The distributor has the hexagonal pocket 41 which receives the hexagonal nut 34 and the hexagonal hub 31, the nut being turned to bring its faces into 115 register with the hub so that the distributor member can be readily applied. The distributor will thus be coupled to the shaft and cam to rotate therewith. At its outer end the distributor has the cylindrical projection 43 for seating in the cylindrical socket 44 provided in the base of the housing 4. Secured in the base of the housing 1 and extending axially into the socket 44 120 is the cylindrical contact post 45 which is 125

received in the cylindrical axial opening 46 in the end of the distributor member. Between the end of the opening and the end of the post is interposed a contact spring 47 whose end extends radially through a passageway 48 where it connects with the projecting end of the commutator brush 40, this brush being engaged by a spring 49 inserted between the end of the brush and the end of the pocket 50 in which the brush is inserted. In the ledge 51 surrounding the socket 44 are seated the commutator segments 51, 52, 53 and 54 spaced ninety degrees apart and connected respectively with the terminal sleeves 55, 56, 57 and 58 which extend upwardly through the extension 59 on the housing 4. This extension also secures the terminal sleeve 60 which is connected with the terminal post 45. The ignition current is delivered to the brush through the sleeve 60, pin 45 and spring 47, and this current is distributed successively to the commutator segments 51, 52, 53 and 54 by the brush as the distributor member rotates with the shaft C and the cam. The frame or housing 4 as well as the distributor member 41 may be constructed of some good insulating material such as fibre or bakelite.

In Fig. 9 I have shown the circuit arrangement for the apparatus. G represents the magneto of a Ford system. As the voltage of the generator is not sufficient to give the necessary high tension current for direct sparking I provide transformer or induction coil mechanism. I provide two transformers or induction coils F and F', each comprising a core 61, a primary winding 62, and a secondary winding 63. One terminal of the generator is grounded, the other terminal connecting through conductor 64 with the primary winding 62. The other end of the primary winding of the induction coil F is connected by conductor 64' with the terminal post 19 of the contact mechanism A, while the primary winding of the coil F' has its other end connected by conductor 65 with the terminal post 18 of the contact mechanism. The terminal post 16 of the contact mechanism is connected to ground through conductor 66. The secondary windings are connected at their one end to conductor 67 which connects with the contact post 45 of the distributor mechanism, this post being connected by the spring 47 with the commutator brush 40. The other ends of the secondary windings are connected with the ground directly or through conductor 64 and the generator as shown. The commutator segments 51, 52, 53 and 54 are connected by conductors 68, 69, 70 and 71 with the respective spark plugs p of the engine cylinders Nos. 1, 2, 3 and 4, the other terminals of the spark plugs connecting with the engine frame E which is grounded.

With the position shown in full lines Fig. 9 the cam tooth 10 is holding up the spring 14 while the diametrically opposite tooth 12 is in advance of the abutment on the lower spring 15. Contacts 22 and 23 are therefore separated and contacts 25 and 26 closed (Fig. 3). The distributor member 38 which, in the arrangement shown, is leading the cam by 30 degrees, will hold the commutator brush 40 on one end of the segment 51, the shaft C rotating in counterclockwise direction. Just before the cam tooth 10 raises the spring 14 current flows from the generator G through conductor 64, both primary windings, both springs, and to ground through conductor 66. The cores of both induction coils are therefore magnetized and current is induced in the secondary windings. When the cam tooth 10 raises the spring 14 the primary circuit of the coil F' is suddenly opened and the induced high voltage secondary current will discharge through conductor 67, the distributor member 38, brush 40, segment 51, conductor 68, spark plug p of cylinder No. 1, and to ground, and from ground through conductor 64 back to the secondary winding, the commutator brush engaging with the end of the commutator segment 51. Before the brush leaves the commutator segment spring 14 will be closed and spring 15 will be depressed by the cam tooth 12 to open the primary circuit of induction coil F at the contacts 25 and 26 as shown by the dotted lines. The secondary winding of this coil will then discharge, the current flowing from the secondary winding through the circuit just traced, and a second intense spark will be produced at the plug of cylinder No. 1. The cam and springs are relatively adjusted to cause opening of one primary circuit for a normal ignition, which, in a Ford engine, would be when the piston is at the end of its compression stroke. The other primary circuit would be opened a short time afterwards to cause a second spark to be delivered to the cylinder. The high compression in the cylinder causes a high resistance between the spark points and a considerable part of the energy of the first spark must be utilized to overcome this resistance, the remaining energy being sometimes insufficient to produce the necessary hot spark for efficient ignition. When the first spark travels across the gap it ionizes the gap and thus reduces the resistance to current flow so that when the second primary circuit is closed the current can produce an intense hot spark, the time interval between openings of the primary circuit being such that the second spark will take advantage of the ionized condition caused by the first spark. If the first spark fails to explode all of the gas the second or follow-up spark will finish the work and thus full efficiency 130

is obtained and the engine will run much cleaner. If the first spark should fail entirely, the second or follow-up spark will cause explosion and thus keep up the power of the engine.

As the distributor member and cam rotate the cylinders in their proper succession are each given a series of sparks for each gas charge. In the arrangement shown two successive sparks are applied to each cylinder for each charge but it is evident that by increasing the number of teeth on the cam a series of three or more sparks could be given each charge of gas. By providing six commutator segments and a corresponding number of cam teeth a six cylinder engine could be served.

Instead of using an alternating current generator as a current source a direct current generator or a battery could be used. In Fig. 9 I show a battery 72 adapted to be switched in circuit in place of the generator. When the battery current flows through a primary circuit and the circuit is then suddenly opened, an intense current flow will be discharged through the secondary circuit which will possess the required sparking strength.

In Fig. 10 I show a slightly modified arrangement, only one induction coil being used. I have shown the induction coil H having the primary winding 73 whose one end is connected by conductor 74 with a battery or generator 75. The other end of the primary winding connects with the spring 14, the contact 26 for the spring 15 being grounded, the springs being thus connected in series. One end of the secondary winding 76 is grounded and the other end is connected by conductor 77 with the traveling distributor member. When the primary circuit is closed the core of the coil will be magnetized and when the primary circuit is opened an induced current flow at high voltage will flow through the secondary circuit to cause efficient sparking. With the positions of the parts shown the spring 14 has just been raised by the cam to open the primary circuit and the induced current discharging through the secondary circuit will give the first spark in cylinder No. 1. Immediately after release of spring 14 the primary circuit will be closed and then the cam will depress spring 15 to again open the circuit so that the second spark will be produced by the discharged secondary current. A single induction coil will do the work when the engine is of low speed, as then the primary winding will have sufficient time between circuit breaks to fully magnetize the core. However where an engine is designed for high speed two or more induction coils are preferable as shown in Fig. 9 for then one coil can be fully magnetized by its primary winding while the primary circuit of

the other core is opened and its secondary circuit is discharging. The arrangement of Fig. 9 is particularly adaptable and efficient in Ford cars, the simple make and break mechanism A doing away with the complicated and unreliable vibrator mechanism on the four coil units of the regular Ford system. With my arrangement the high frequency generator is connected directly through the induction coils with the spark plugs under control of the distributor.

I do not desire to limit myself to the exact construction, arrangement and operation as shown as changes and modifications can be made within the scope of the invention.

I claim as follows:

1. In an ignition system for explosive engines, the combination of two induction coils each comprising a primary winding and a core and a secondary winding, a primary circuit including said primary windings in parallel, a secondary circuit including said secondary windings in parallel, a source of current connected with said primary circuit, distributor mechanism for closing said secondary circuit in seriatim through the spark plugs of the engine, and interrupter mechanism driven in timed relationship with the distributor mechanism to alternately interrupt the current flow through said primary windings during each closure of the secondary circuit through a spark plug by the distributor mechanism whereby two distinct sparks will be produced at each spark plug during closure of the secondary circuit therethrough.

2. In an ignition system for explosive engines having a multiplicity of cylinders, the combination of two induction coils each having a primary winding and a secondary winding, a primary circuit including both primary windings, a source of current connected with said primary circuit, a secondary circuit including both secondary windings, distributor mechanism for closing said secondary circuit in seriatim through the spark plugs of the engine cylinders, and interrupter mechanism driven in timed relationship with said distributor mechanism, said interrupter mechanism being adapted to cause a series of interruptions of the current flow through said primary circuit during each closure of the secondary circuit through one of said spark plugs, each interruption causing a discharge of ignition current through the secondary circuit and a distinct spark at the respective spark plug, whereby each plug will receive a series of distinct sparks.

3. In an ignition system for explosive engines, the combination of a plurality of induction coils each having a primary winding and a secondary winding, a primary circuit including said primary windings in parallel,

- a source of current connected with said primary circuit, a secondary circuit including said secondary windings in parallel, a spark plug connected in said secondary circuit, and means for successively opening the primary winding branches whereby to cause a succession of induced current discharges through the secondary circuit and through said spark plug.
4. In an ignition system, the combination of inductively related primary and secondary circuits, a spark plug connected in the secondary circuit, a source of current for the primary circuit, a plurality of circuit controllers for said primary circuit, and means for engaging successively with and operating said circuit controllers during each ignition period of the engine with which the spark plug is associated, the operation of each circuit controller controlling the primary circuit to cause a flow of secondary current and a spark at the spark plug whereby a plurality of distinct sparks are caused at said spark plug during each ignition period.
5. In an ignition system for explosive engines, the combination of induction mechanism comprising a primary winding and a secondary winding, a primary circuit, a source of current for said primary circuit, a secondary circuit, means for closing said secondary circuit in seriatim through the spark plugs of the engine, a plurality of circuit controllers connected with said primary circuit, and means for successively operating said circuit controllers during each period of closure of the secondary circuit through a spark plug, said primary circuit being interrupted by the operation of each controller to thereby cause induced current flow through the secondary winding whereby a plurality of distinct sparks will be caused at each spark plug during the ignition period of the corresponding engine cylinder.
6. In an ignition system for explosive engines, the combination of inductively related primary and secondary circuits, a source of current for the primary circuit, a spark plug connected in the secondary circuit, a rotary cam having opposed cam projections, circuit controlling springs on opposite sides of said cam having abutments in the paths of said projections, said abutments being circumferentially offset whereby rotation of said cam will cause successive cooperation of said projections with said abutments and operation of said springs to successively inter-
- rupt the primary circuit, and means for keeping said secondary circuit closed through said spark plug during such successive interruptions of the primary circuit whereby a succession of sparks will be produced at said plug.
7. In an ignition system, the combination of inductively related primary and secondary circuits, a spark plug connected with the secondary circuit, a source of current for the primary circuit, a plurality of circuit controllers normally closing said primary circuit, and means for successively operating said circuit controllers during each ignition period of the engine with which the spark plug is associated, the operation of each controller independently causing opening of the primary circuit and thereby induced current flow through the secondary circuit and spark plug whereby a plurality of distinct sparks is caused at said spark plug during each ignition period.
8. In an ignition system, the combination of inductively related primary and secondary circuits, a spark plug connected with the secondary circuit, a source of current for the primary circuit, a plurality of circuit controllers for said primary circuit, each adapted when operated to change the condition of the primary circuit to cause induced current flow through the secondary circuit and said plug, and means for effecting successive operation of said controllers during each ignition period of the engine with which the spark plug is associated, whereby a plurality of distinct successive sparks will be produced at said spark plug during each ignition period.
9. In an ignition system for explosive engines, the combination of a plurality of induction coils each having a primary winding and a secondary winding, a primary circuit including said primary windings, a source of current connected with said primary circuit, a secondary circuit including said secondary windings, a spark plug connected with said secondary circuit, and means for successively controlling said primary windings to cause a succession of induced current discharges through the secondary circuit and through said spark plug during each ignition period of the engine with which the spark plug is connected.

In witness whereof, I hereunto subscribe my name this 26 day of June A. D., 1922.

ALONZO HOWARD.
